EQUIPMENT FOR HOLDING OILS AND
OTHER LIQUIDS

Solomon Burwen, Lynn, Mass.

Application April 3, 1933, Serial No. 664,102

2 Claims. (Cl. 221—80)

This invention relates to equipment for holding oils and other liquid commodities such as are stored and sold in automobile service stations, paint and hardware stores, and similar establishments.

It has for its purposes the conservation of floor space in such places as such commodities are stored and sold; to provide a new and improved storage and dispensing unit in sections placed one above the other for storing and dispensing said commodities so as to require no greater floor space than is normally occupied by a single dispensing unit; to thereby minimize overhead and rental charges; to render possible the storage of a greater number of grades or kinds of liquid commodities than has heretofore been possible in a given floor area; to render immediately accessible for dispensation a greater number of kinds or grades of liquid commodities than has heretofore been readily accessible on a given floor area; to provide a readily accessible means for filling such containers; to provide readily accessible means for gaging the contents at any desired time; to provide convenient means for withdrawing the liquid from said containers; to provide means for cleaning the containers; to provide a new and improved inter-engaging and aligning device for said units when stacked vertically one upon the other; to provide means insuring the exhausting of the container contents by the emptying means; and to provide the various other advantages and results made evident from the following specification.

I accomplish the objects of my invention as shown in the accompanying drawings by providing a series of containers in unit formation, placed one above the other to any desired height so that the entire series of containers occupies no more floor space than has heretofore been required for one container, and by providing therefor suitable means for filling, for gaging, for emptying, and for cleaning when required.

Referring to the accompanying drawings which form a part of this specification and in which similar letters of reference refer to similar parts throughout the various views, Figure 1 shows a front view of my device which comprises two container tanks, one of which is positioned above the other. The lower tank is shown with the refilling orifice open, ready to receive liquid. The drip pan on the upper tank is placed vertically so as to allow free access to the refilling orifice. The remaining parts are in normal position as maintained when in use.

Figure 2 shows a section taken on line 2—2 in Figure 1.

Figure 3 shows a section taken on line 3—3 in Figure 1.

Figure 4 shows a side view of Figure 1, both 60 refilling openings being closed.

Referring again to the drawings, it will be seen that my device consists of a series of tanks A, upon each of which is mounted a pump B. Projecting from the front of the tank is a refilling duct C which is open at the top D, and has a cover E, hinged at F. The projections G on the cover, and G¹ on the duct C, provide a means of locking the cover E with a padlock H. Another projection J, protruding from the front, and open at the top K, is designed to permit a graduated measuring stick L to be inserted in the tank for the purpose of measuring the contents therein. The measuring stick L is preferably made a part of the cap M. The cap M is used to cover the opening K to exclude dirt or other foreign matter from the tank. The opening K is so designed that the measuring stick L will always enter the tank at the same angle. The pump may be of any standard type which fits the 80 purpose, but the type here shown is preferable. The pump B is operated by a handle B¹ which operates a shaft B², and said shaft operates the pump mechanism. The handle B¹ travels through an arc of 90° to obtain the best operating conditions. The discharge pipe O and outlet nozzle P are elevated above the tanks to avoid leakage when tanks are filled or being refilled. The opening D is positioned above the nozzle P so that a 90 refilling container can conveniently rest upon the edge of opening D without placing weight upon the nozzle P or discharge pipe O. The body portion of the pump shown is preferably made in two major parts, an inner and an outer section, the inner section B³ being positioned inside the 95 tank A. An opening A¹ on the top of the tank is provided for the dual purpose of rendering it convenient to clean the interior of the containers, and for putting the inner pump section B³ in place, and the bolts A² can be readily held while 100 nuts A⁴ are being tightened. The opening A¹ is covered with a cap A³. The tanks are adaptable to be placed on top of each other and are held in place by the angle irons R in each corner of the tank. These angle irons project below the bottom 105 of the tank and onto the top of another tank placed therebeneath. The tops of the angle irons R are distanced from the top of the tank to which they are secured, equal to the projection of angle irons R below the bottom of the tank. The drip 110

pan S is hinged at T that it may be placed in an upright position as shown on the top tank in Figure 1, and thus allow refilling of the tank below or in a horizontal position for general use.

5 While I have illustrated and described a preferred construction for carrying my invention into effect, this is capable of variation or modification without departing from the spirit of the invention. I therefore do not wish to be limited
10 to the exact details of construction herein set forth, but desire to avail myself of such variations and modifications as come within the scope of the appended claims.

Having thus described my invention, I claim as
15 new and desire to secure by Letters Patent of the United States of America:—

1. A device of the class described comprising a pair of containers of similar form and size, said

containers being adapted to be stacked one on the other, each container having angle brackets depending from the bottom thereof and constituting legs for the respective containers, each container having on one end a pump and a filling duct, the brackets of the uppermost container being adapted to fit over the corners of the lowermost container with their lower ends abutting the uppermost ends of the brackets of the lowermost container, said brackets when so engaged serving to maintain the pumps and filling ducts in vertical alinement.

2. A device as claimed in claim 1, wherein each pump is provided with a discharge pipe, the discharge ends of the respective pipes being arranged in planes above the tops of the respective containers.

SOLOMON BURWEN.
